UNITED STATES PATENT OFFICE.

FRIEDRICH W. KLEVER, JR., OF SOLINGEN, GERMANY.

SCISSORS.

SPECIFICATION forming part of Letters Patent No. 681,327, dated August 27, 1901.

Application filed October 16, 1900. Serial No. 33,206. (No model.)

To all whom it may concern:

Be it known that I, FRIEDRICH WILHELM KLEVER, Jr., merchant, a citizen of Germany, and a resident of Solingen, Rhineland, Germany, have invented certain new and useful Improvements in a Pair of Scissors Which Can be Used at the Same Time as Calipers, of which the following is a specification.

This invention relates to buttonhole-scissors, which may be accurately gaged and set to cut buttonholes of different sizes.

In the accompanying drawings, Figure 1 is a side view of my improved scissors; Fig. 2, a similar view showing the opposite side, and Fig. 3 a side view showing the scissors partly open.

The letters *a a* represent the handles of the scissors, the blades of which have the usual notches *i* for starting the buttonhole. Near its rear end one of the blades is provided with a scale *s*, concentric to the pivot, while the other blade is cut away at its rear end to expose such scale, and is provided with a pointer *z*, moving along the same. In order to con-

trol the degree to which the scissors may be 25 opened, and consequently the size of the buttonhole, a set-screw or adjustable stop *m* is arranged between the rear ends of the blades.

In use the scale is set to the size of the buttonhole desired and then the set-screw is adjusted to permit a corresponding limited opening of the blades. The buttonholes may now be cut and will all be of the size desired, which will be maintained until a new adjustment is effected. 35

What I claim is—

Buttonhole-scissors having notched blades, a scale concentric to the scissors-pivot on one blade, a cut-away section and pointer on the other blade, and an adjustable stop between 40 the rear ends of the blades, substantially as specified.

Signed by me at Solingen, Germany, this 3d day of October, 1900.

F. W. KLEVER, JR.
